A. CECH

SWIMMING FOOT PADDLE

Filed May 6, 1924

INVENTOR
Andrew Cech

BY
S. H. Plachek
ATTORNEY

UNITED STATES PATENT OFFICE.

ANDREW CECH, OF NILES, OHIO.

SWIMMING FOOT PADDLE.

Application filed May 6, 1924. Serial No. 711,323.

To all whom it may concern:

Be it known that I, ANDREW CECH, citizen of the United States, residing at Niles, in the county of Trumbull and State of Ohio, have invented certain new and useful Improvements in Swimming Foot Paddles, of which the following is a specification.

This invention relates generally to appliances for use by swimmers to enable the latter to propel themselves at increased speed through the water, the invention having particular reference to a device of this sort adapted to be applied to the feet of the swimmer and which I therefore term a swimmer's foot paddle.

The invention has for an object the provision of a novel and simple device of this sort which can be readily applied to and removed from the foot, and which has incorporated therewith means for varying the resistance it offers to the backward thrust of the foot of the user.

For further comprehension of the invention, and of the objects and advantages thereof, reference will be had to the following description and accompanying drawing, and to the appended claims in which the various novel features of the invention are more particularly set forth.

Fig. 1 of the drawing is a plan view showing my improved foot paddle.

Fig. 2 is an end view thereof.

Fig. 3 is a side view.

Fig. 4 is a fragmentary longitudinal vertical sectional view taken on the line 4—4 of Fig. 2.

Fig. 5 is a fragmentary horizontal sectional view taken on the line 5—5 of Fig. 2.

Fig. 6 is a plan view showing a slightly modified form of the paddle.

Referring now to the drawing, my improved foot paddle comprises a central board 10 of a dimension slightly greater than that of the foot of the user and which has fixed thereon a moccasin 11 which receives the foot of the user, a strap 12 being here shown as secured to the board and adapted to be buckled over the user's foot.

Hinged to the central board, as by the pairs of hinges 15 are the side wings or flaps 16 which are arranged to swing backwardly to positions at right angles to the board when the device is drawn forward through the water, and which tend to straighten out

when the swimmer thrusts his foot backward.

I preferably provide adjustable means to limit the said straightening out movement of the wings 16. As here shown a pair of straps 17 are employed and are attached at one end to the respective wings on the rear sides thereof, and pass rearwardly over the abutment posts 18 which are hinged at their forward ends as at 19 to the sides of the board 10, the other ends of these straps being fastened to the said central board 10. Adjacent their last named ends these straps 17 pass through the slotted heads 20 of screws 21 which pass freely through ears 22 on the underside of the board and have nuts 23 threaded on their opposite ends, the screws 21 extending transversely of the board and being engaged with the straps 17 in a manner to tighten the latter, that is to shorten their effective length, when the nuts 23 are turned to move the screws outwardly. The posts 18 are formed at their free ends with rectangular apertures such as 25 through which the straps 17 pass, blocks 26 being slidable along these apertures and being adapted to be engaged by screws such as 27 to clamp the straps between the blocks and the front walls of the said apertures. As will be apparent the spread of the wings may be varied by tightening or loosening the straps 17.

In the construction shown in Fig. 6 the central board 10' is narrowed at the rear end to conform to the shape of the swimmer's foot, while the side wings 16' are correspondingly shaped. A handle 30 is here shown as attached to the front end of the board 10'.

Having thus described my invention what I claim as new and desire to protect by Letters Patent of the United States is as follows:

1. A swimmer's foot paddle comprising a central board provided with means for attachment to the foot, and side wings hinged to said central board, and means for varying the spread of said wings when extended, comprising straps attached at one end to said wings and at opposite ends to said central board.

2. A swimmer's foot paddle comprising a central board provided with means for attachment to the foot, and side wings hinged to said central board, straps attached at one

end to said wings and at opposite ends to the central board for limiting the forward swinging movement of the wings, and abutment elements hinged to and projecting rearwardly from said central board and having the straps passing thereover.

5. A swimmer's foot paddle comprising a central board provided with means for attachment to the foot, and side wings hinged 10 to said central board, straps attached at one end to said wings and at opposite ends to the central board for limiting the forward swinging movement of the wings, and abutment elements hinged to and projecting rearwardly from said central board and having the straps passing thereover, and means engaged with said straps to vary the effective length thereof.

4. A swimmer's foot paddle comprising a central board provided with means for attachment to the foot, and side wings hinged 20 to said central board, straps attached at one end to said wings and at opposite ends to the central board for limiting the forward

swinging movement of the wings, and abutment elements hinged to and projecting rearwardly from said central board and having the straps passing thereover, and means engaged with said straps to vary the effective length thereof, comprising screws mounted on said central board for transverse adjustment thereon and having slotted heads through which the said heads pass.

5. A swimmer's foot paddle comprising a central board provided with means for attachment to the foot, and side wings hinged to said central board, straps attached at one end to said wings and at opposite ends to the central board for limiting the forward swinging movement of the wings, and abutment elements hinged to and projecting rearwardly from said central board and having the straps passing thereover, and means for releasably securing the said straps to the said abutment elements.

In testimony whereof I have affixed my signature.

ANDREW CECH
